(57) **ABSTRACT**

Provided is an ink jet printer including an electromagnetic wave generator that includes an electromagnetic wave generation section, a high-frequency voltage generation section, a transmission line, an ink jet head, and a control section. The electromagnetic wave generation section includes a first electrode, a second electrode, a first coil coupled to the first electrode or the second electrode in series, an impedance matching circuit constituted by a second coil and a capacitor coupled between the first coil and the high-frequency source. A thin ink film discharged from the ink jet head and attached to the recording medium is heated and dried by the electromagnetic wave generator. The control section controls a constant of the second coil or a constant of the capacitor of the impedance matching circuit according to information on the thin ink film.

INK JET PRINTER

The present application is based on, and claims priority from JP Application Serial Number 2019-121932, filed Jun. 28, 2019, the disclosure of which is hereby incorporated by reference here in its entirety.

BACKGROUND

1. Technical Field

The present disclosure relates to an ink jet printer.

2. Related Art

Various types of ink jet recording devices have been developed. For example, a technology for printing on a medium to which ink is unlikely to permeate, such as a film or a metal sheet, has been developed. When ink is attached to such a medium that hardly absorbs ink, for awhile after the attachment, the ink droplets can flow on the medium, and color mixing between dots and bleeding of an image is likely to occur. As one of the measures for suppressing such a phenomenon, it is conceivable to dry the ink in as short a time as possible after the attachment of the ink droplet.

As a method for drying ink, for example, it is conceivable to apply a heated solid to the back surface of the medium and dry a film of ink droplets attached to the surface by heat conduction but the energy required for this is very large, and it takes time for the heat to be conducted, which is not always the optimal method. Further, as another method, in a drying device described in JP-A-2017-165000, an attempt has been made to dry ink by applying an AC electric field to the medium and dielectrically heating the attached ink.

However, in the device described in JP-A-2017-165000, a grounded conductor rod and a conductor rod for applying a high-frequency voltage to both ends are arranged in parallel and separated from each other, so that a high-frequency radiation device such as a loop antenna is used. From such a radiation device, electromagnetic waves are radiated over a relatively wide range due to the characteristics of the antenna. Therefore, a large amount of power is radiated in addition to the power supplied to the ink film to be heated, and it is considered that energy efficiency is low and it is necessary to shield diverging electromagnetic waves. Further, depending on the printing pattern, there is an area where ink does not exist, and although this exists intricately with an area where ink exists, the electromagnetic waves are also injected into such an area, resulting in poor energy efficiency.

SUMMARY

An ink jet printer according to an aspect of the present disclosure includes: an electromagnetic wave generator that includes an electromagnetic wave generation section that generates an electromagnetic wave, a high-frequency voltage generation section that generates a voltage applied to the electromagnetic wave generation section, and a transmission line that electrically couples the electromagnetic wave generation section and the high-frequency voltage generation section to each other in which the electromagnetic wave generation section includes a first electrode, a second electrode, a first conductor that electrically couples the first electrode and the transmission line to each other, and a second conductor that electrically couples the second electrode and the transmission line to each other, one of the first

electrode or the second electrode is a reference potential electrode to which a reference potential is applied and the other is a high-frequency electrode to which a high-frequency voltage is applied, a minimum separation distance between the first electrode and the second electrode is $\frac{1}{10}$ or less of a wavelength of an output electromagnetic wave, a minimum separation distance between the first conductor and the second conductor is $\frac{1}{10}$ or less of a wavelength of an output electromagnetic wave, and the first conductor further includes a coil, and the coil is disposed at a position closer to the first electrode than the transmission line; and an ink jet head discharging ink, in which a plurality of the electromagnetic wave generators are provided and the electromagnetic wave generators are moved relative to a recording medium, a thin ink film of the ink discharged from the ink jet head and attached to the recording medium is heated and dried by the electromagnetic wave generator, and a control section that controls a power or a frequency of the high-frequency source according to information on the thin ink film is further included.

In the ink jet printer according to the aspect, a memory for storing an optimum value in accordance with the information on the thin ink film may be further included, in which the control section may control the power or the frequency of the high-frequency source with reference to the optimum value.

An ink jet printer according to another aspect of the present disclosure includes: an electromagnetic wave generator that includes an electromagnetic wave generation section that generates an electromagnetic wave, a high-frequency voltage generation section that generates a voltage applied to the electromagnetic wave generation section, and a transmission line that electrically couples the electromagnetic wave generation section and the high-frequency voltage generation section to each other in which the electromagnetic wave generation section includes a first electrode, a second electrode, a first conductor that electrically couples the first electrode and the transmission line to each other, and a second conductor that electrically couples the second electrode and the transmission line to each other, one of the first electrode or the second electrode is a reference potential electrode to which a reference potential is applied and the other is a high-frequency electrode to which a high-frequency voltage is applied, a minimum separation distance between the first electrode and the second electrode is $\frac{1}{10}$ or less of a wavelength of an output electromagnetic wave, a minimum separation distance between the first conductor and the second conductor is $\frac{1}{10}$ or less of a wavelength of an output electromagnetic wave, a first coil is coupled to the first electrode or the second electrode in series, the first conductor includes the first coil, and the first coil is disposed at a position closer to the first electrode than the transmission line, and an impedance matching circuit constituted by a second coil and a capacitor is coupled between the first coil and the high-frequency source; and an ink jet head discharging ink, in which one or more electromagnetic wave generators are provided and the electromagnetic wave generator is moved relative to a recording medium, a thin ink film of the ink discharged from the ink jet head and attached to the recording medium is heated and dried by the electromagnetic wave generator, and a control section that controls a constant of the second coil or a constant of the capacitor of the impedance matching circuit according to information on the thin ink film is further included.

In the ink jet printer according to the aspect, a memory for storing an optimum value in accordance with the information

tion on the thin ink film may be further included, in which the control section may control the constant of the second coil or the constant of the capacitor of the impedance matching circuit with reference to the optimum value.

In the ink jet printer according to any of the aspects, the information on the thin ink film may be selected from a printing pattern, an amount of the ink, a type of the ink, and a combination thereof.

BRIEF DESCRIPTION OF THE FIGURE

FIG. 1 is a schematic diagram showing the vicinity of an electrode of an electromagnetic wave generator according to an embodiment.

FIG. 2 is an equivalent circuit diagram of the electromagnetic wave generator according to the embodiment.

FIG. 3 shows an electric field density distribution when a coil is disposed near an electrode according to the embodiment.

FIG. 4 shows an electric field density distribution when a coil is disposed in a distant place of an electrode according to the embodiment.

FIG. 5 is a schematic diagram showing the vicinity of an electrode of the electromagnetic wave generator according to the embodiment.

FIG. 6 is a schematic diagram showing the vicinity of an electrode of the electromagnetic wave generator according to the embodiment.

FIG. 7 is a schematic diagram of a disposition of a first electrode and a second electrode of an ink dryer with respect to a thin ink film as viewed from the side.

FIG. 8 is a schematic diagram showing an aspect in which a thin ink film is disposed between parallel plate electrodes.

FIG. 9 is a schematic diagram showing an aspect in which a thin ink film is disposed between the parallel plate electrodes.

FIG. 10 shows an example of an equivalent circuit when a thin ink film is disposed between the parallel plate electrodes.

FIG. 11 is a schematic diagram of the vicinity of electrodes and a disposition of a conductor plate of the ink dryer according to the embodiment, as viewed from the side.

FIG. 12 is a schematic diagram of a main part of an ink jet printer according to the embodiment.

FIG. 13 is a schematic diagram of a main part of the ink jet printer according to the embodiment.

FIG. 14 is a functional block diagram of the ink jet printer according to the embodiment.

FIG. 15 is an equivalent circuit diagram of an electromagnetic wave generator according to a modification example.

FIG. 16 is an equivalent circuit diagram of the electromagnetic wave generator according to the modification example.

FIG. 17 is an equivalent circuit diagram of the electromagnetic wave generator according to the modification example.

FIG. 18 shows a simulation result of a state in which a resonance frequency and an impedance of the electromagnetic wave generator fluctuate with a printing pattern of the thin ink film.

DESCRIPTION OF EXEMPLARY EMBODIMENTS

An embodiment of the present disclosure will be described below. The embodiment described below

describes an example of the present disclosure. The present disclosure is not limited to the following embodiment at all, and includes various modifications implemented without departing from the spirit of the present disclosure. Note that not all of the configurations described below are essential configurations of the present disclosure.

1. INK JET PRINTER

10 An ink jet printer according to the present embodiment includes a first electrode and a second electrode, and includes an electromagnetic wave generator in which a coil is coupled in series to the first electrode or the second electrode, a carriage, and an ink jet head. The carriage has the electromagnetic wave generator and the ink jet head mounted thereon, and a thin ink film of ink discharged from the ink jet head and attached to a recording medium is dried by the electromagnetic wave generator, the carriage, and the ink jet head will be described in this order.

1.1. Electromagnetic Wave Generator

The electromagnetic wave generator of the present embodiment includes an electromagnetic wave generation section that generates an electromagnetic wave, a high-frequency voltage generation section that generates a voltage applied to the electromagnetic wave generation section, and a transmission line for electrically coupling the electromagnetic wave generation section and the high-frequency voltage generation section to each other. The electromagnetic wave generation section includes a first electrode, a second electrode, a first conductor for electrically coupling the first electrode and the transmission line to each other, and a second conductor for electrically coupling the second electrode and the transmission line to each other. Further, the first conductor includes a coil, and the coil is provided at a position closer to the first electrode than the transmission line.

Therefore, the electromagnetic wave generator of the present embodiment includes at least a first electrode, a second electrode, and a coil. FIG. 1 is a schematic diagram showing the vicinity of the electrode of the electromagnetic wave generator 10 according to an embodiment. FIG. 2 is an equivalent circuit diagram of the electromagnetic wave generator 10. The electromagnetic wave generator 10 includes an electromagnetic wave generation section including a first electrode 1, a second electrode 2, and a coil 3, a coaxial cable 4 as a transmission line, and a high-frequency source as a high-frequency voltage generation section.

Regarding the coil mentioned here, even with the same inductance, a heating energy efficiency of an ink film greatly differs depending on a position where the coil is inserted in series, and it is desirable to install the coil as close to the electrode as possible. The coil 3 may be omitted by giving the electrode itself an inductance by, for example, forming the first electrode or the second electrode in a meander shape.

1.1.1 Electrode

The electromagnetic wave generator 10 includes a first electrode 1 and a second electrode 2. The first electrode 1 and the second electrode 2 have conductivity. A reference potential is applied to one of the first electrode 1 and the second electrode 2. A high-frequency voltage is applied to the other of the first electrode 1 and the second electrode 2. The method of selecting the first electrode 1 and the second electrode 2 can be any methods. The reference potential is applied to one of the two electrodes, and a high-frequency voltage is applied to the other. In this specification, an

electrode to which a reference potential is applied may be referred to as a "reference potential electrode", and an electrode to which a high-frequency voltage is applied may be referred to as a "high-frequency electrode".

The reference potential is a constant potential serving as a reference for a high-frequency voltage, and may be, for example, a ground potential. As a special example, if an output of the high-frequency voltage generation circuit that generates a high-frequency voltage to be input to the electromagnetic wave generator 10 is a differential circuit, there is no distinction between the first electrode 1 and the second electrode 2. As for a frequency of the high-frequency, there is a heating effect when the frequency is 1 MHz or more, but since a dielectric loss tangent becomes a maximum around 20 GHz, the heating efficiency also becomes the maximum therearound. In particular, from the viewpoint of heating water, the bandwidth is desirably 2.0 GHz or more and 3.0 GHz or less, and from a legal viewpoint, a 2.4 GHz bandwidth, which is one of the ISM bandwidth, is desirable, for example, 2.44 GHz or more and 2.45 GHz or less. The higher the high-frequency voltage, the greater the amount of heat supplied to the ink. However, since the voltage is normally transmitted to the electromagnetic wave generator 10 through a 50Ω transmission line, at the high-frequency voltage input of the electromagnetic wave generator 10, a voltage is represented by "high-frequency power=V^2/R=V^2/50". Furthermore, in order to suppress the amount of heat generated by the parasitic resistance of the electromagnetic wave generator 10, the power per electromagnetic wave generator 10 is set to about 10 W, and it is desirable to use a plurality of electromagnetic wave generators 10 to ensure the power required for drying the ink. Further, the ink is heated by dielectric heating due to an electric field generated between the first electrode 1 and the second electrode 2. At this time, the electric field between the first electrode and the second electrode has a value of about 1×10^6 V/m by the effect of the coil 3 or the distance between the electrodes.

The application of the high-frequency voltage means that the central portion of a surface of the first electrode 1 or the second electrode 2 opposite to a surface facing the ink is set to a feeding point, and the power of the above described high-frequency voltage is supplied to this feeding point. Incidentally, as shown in FIG. 6, which will be described later, a coating portion of the coaxial cable may be connected to the electrode with a metal surface.

In the illustrated example, the first electrode 1 and the second electrode 2 have a flat plate shape. The plane shape of the first electrode 1 and the second electrode 2 can be any shapes, and may be, for example, a square, a rectangle, a circle, or a combination of these shapes. In the illustrated example, the first electrode 1 and the second electrode 2 have a substantially square shape in plan view. The plane size of the first electrode 1 and the second electrode 2 is 0.01 cm² or more and 100.0 cm² or less, desirably 0.1 cm² or more and 10.0 cm² or less, more desirably 0.5 cm² or more and 2.0 cm² or less, and further desirably 0.5 cm² or more and 1.0 cm² or less on one electrode, as an area in plan view. The area of the first electrode 1 and the second electrode 2 in plan view may be the same or different. The plan view refers to a state viewed from the z direction in FIG. 1.

It is desirable that the first electrode 1 and the second electrode 2 are disposed so as not to overlap with each other in plan view. In the illustrated example, the first electrode 1 and the second electrode are disposed in parallel on the same plane. With such a disposition, a predetermined electromagnetic wave can be generated efficiently. The shapes and

dispositions of the first electrode 1 and the second electrode 2 will be further described later. The details of the generated electromagnetic waves will be described later.

The first electrode 1 and the second electrode 2 are formed of a conductor. Examples of the conductor include metals, alloys, and conductive oxides. The first electrode 1 and the second electrode 2 may be the same material or different materials. The first electrode 1 and the second electrode 2 may be appropriately formed by selecting the thickness or strength so that the first electrode 1 and the second electrode 2 can be self-supporting, or can be formed on a surface of a substrate or the like made of a material (not shown) having a low dielectric loss tangent that transmits electromagnetic waves when it is difficult to maintain the strength of the first electrode 1 and the second electrode 2.

Each of the first electrode 1 and the second electrode 2 are electrically coupled to a coaxial cable 4 coupled to the high-frequency source via an inner conductor 4a and an outer conductor 4b, as schematically shown in FIG. 1. The inner conductor 4a is disposed on a surface of the first electrode 1 opposite to a surface facing the thin ink film, and the outer conductor 4b is disposed on a surface of the second electrode 2 opposite to a surface facing the thin ink film. In other words, the first electrode 1 and the second electrode 2 are disposed closer to the thin ink film than the inner conductor 4a and the outer conductor 4b.

1.1.2. Electrode Interval

The minimum separation distance d between the first electrode 1 and the second electrode 2 is $\frac{1}{10}$ or less of the wavelength of the electromagnetic wave output from the electromagnetic wave generator 10. For example, when the frequency of the electromagnetic wave output from the electromagnetic wave generator 10 is 2.45 GHz, the wavelength of the high-frequency is substantially 12.2 cm, and in this case, the minimum separation distance between the first electrode 1 and the second electrode 2 is substantially 1.22 cm or less. In the example in FIG. 1, the coil 3 is provided on the internal conductor 4a. The distance between the coil 3 and the first electrode 1 in the transmission line of the inner conductor 4a is desirably shorter than the distance between the coil 3 and the coaxial cable 4. Normally, the coil 3 is coupled only to the first electrode, but can be coupled only to the second electrode or to both the first electrode and the second electrode.

By setting the minimum separation distance d between the first electrode 1 and the second electrode 2 to be $\frac{1}{10}$ or less of the wavelength of the output electromagnetic wave, most of the electromagnetic waves generated when a high-frequency voltage is applied can be attenuated near the first electrode 1 and the second electrode 2. Thereby, the intensity of the electromagnetic wave reaching the distant place from the first electrode 1 and the second electrode 2 can be reduced.

That is, the electromagnetic wave radiated from the electromagnetic wave generator 10 is very strong near the first electrode 1 and the second electrode 2 and very weak far from the first electrode 1 and the second electrode 2. In this specification, an electromagnetic field generated by the electromagnetic wave generator 10 near the first electrode 1 and the second electrode 2 may be referred to as a "near electromagnetic field". Further, in this specification, an electromagnetic field generated by a general antenna (antenna) for transmitting electromagnetic waves to a distant place may be referred to as a "distant electromagnetic field". Note that the boundary between the near and far distances is

a position separated from the electromagnetic wave generator **10** by substantially 1/6 of the wavelength of the generated electromagnetic wave.

The electromagnetic wave generator **10** is used for applications such as televisions and mobile phones, and is not an electromagnetic wave generator that transmits electromagnetic waves at intervals of m units. Instead, the electromagnetic wave generator **10** is an electromagnetic wave generator in which during the transmission of the distance of 1/6 of the wavelength of the generated electromagnetic wave, the electric field density of the electromagnetic wave is attenuated to 30% or less of the electric field density between the first electrode **1** and the second electrode **2**. That is, the electromagnetic wave generator **10** is not suitable for a communication. Furthermore, since the electromagnetic wave generated by the electromagnetic wave generator **10** has a high attenuation rate, the range of the electric field is suppressed. Therefore, unnecessary radiation hardly occurs in an area farther from the device than the distance of substantially the wavelength of the generated electromagnetic wave. Therefore, it is unnecessary or easy to comply with regulations by the Radio Law and the like, and even when compliance is required, it is possible to reduce the scattering of electromagnetic waves to the periphery of the electromagnetic wave generator by a simple electromagnetic wave shield or the like. Such properties of the electromagnetic wave generator **10** are caused by the small size of the electrodes, the short distance between the electrodes, the difficulty of resonance, and the like.

In other words, the electromagnetic wave generator **10** of the present embodiment is not a device for generating a distant electromagnetic field such as a dipole antenna, but is equivalent to a slot antenna where the negative/positive is inverted with respect to the dipole antenna and the slot width is made sufficiently small with respect to the wavelength to make it difficult to generate distant electromagnetic fields. The present structure only generates an electric field like a capacitor, and this electric field does not generate a magnetic field as a secondary matter. Therefore, a so-called distant electromagnetic field in which an electric field and a magnetic field are generated in a chain and an electromagnetic wave is transmitted to a distant place is not generated.

1.1.3. Coil

The electromagnetic wave generator **10** includes a coil **3**, and the coil **3** is coupled to the first electrode **1** or the second electrode **2** in series, and coupled as close to the first electrode **1** or the second electrode **2** as possible. The first electrode **1** or the second electrode **2** is coupled to a path to which a high-frequency voltage is applied via the coil **3**.

The coil **3** is installed for three purposes: matching, increasing an electric field generated between electrodes, and enhancing by adding an electric field generated by a coil to an electric field generated between electrodes.

Role of Coil (1): Matching

Generally, a voltage applied to an antenna is transmitted to the antenna via a coaxial cable (for example, a characteristic impedance of 50Ω). It is desirable that the impedance of the antenna matches the impedance of the high-frequency voltage generation circuit or the impedance of the coaxial cable transmitted from the circuit to the antenna. By matching or approaching the impedance of the antenna to the impedance of a cable or the like, the energy transmission efficiency is improved. Conversely, when a high-frequency voltage of a sine wave is input to the antenna and the impedance of the high-frequency voltage generation circuit does not match the impedance of the antenna, signal reflection occurs at a discontinuous place of impedance, and it is

difficult to input a signal to the antenna. Therefore, at the coupling place between the antenna and the coaxial cable where impedance discontinuity is likely to occur, a matching circuit constituted by a coil and a capacitor is inserted, the impedance of the antenna is adjusted, and the energy transmission efficiency improvement is performed between the inner conductor of the coaxial cable and the electrode of the antenna, or between the outer conductor and the electrode of the antenna. The coaxial cable is normally 50Ω, and the matching circuit is adjusted so that the antenna also has 50Ω. If the coaxial cable has an imaginary impedance, the antenna is adjusted to an imaginary impedance conjugate to the imaginary impedance. Such a coil is called a so-called matching coil.

Role of Coil (2): Increasing Electric Field Density Between Electrodes

FIG. 2 is an equivalent circuit of the ink dryer. The electromagnetic wave generation circuit A corresponds to the electromagnetic wave generator **10**. The capacitor C of the electromagnetic wave generation circuit A corresponds to the first electrode **1** and the second electrode **2**, and the resistance R of the electromagnetic wave generation circuit A corresponds to the radiation resistance of the radiated electromagnetic wave. The high-frequency source corresponds to the high-frequency voltage generation circuit B, and the resistance R of the high-frequency voltage generation circuit B is an internal resistance of the high-frequency voltage source. The coil L inserted between the high-frequency voltage generation circuit B and the electromagnetic wave generation circuit A corresponds to the coil **3** coupled to the first electrode **1** or the second electrode **2** in series.

As described above, since the electromagnetic wave generation circuit A includes the capacitor C, a specific resonance frequency can be obtained by coupling the coil L so as to be in series with the capacitor C. Further, when the inductance of the coil L is increased and the capacitance of the capacitor C is reduced as much as possible, the transmission efficiency is improved. The inductance of the coil L and the capacity of the capacitor C are appropriately designed.

The radiation resistance is smaller (for example, substantially 7Ω) than the impedance of the coaxial cable **4** (for example, 50Ω), and the capacity of the capacitor C apparently formed by the first electrode **1** and the second electrode **2** is, for example, substantially 0.5 pF.

In the electromagnetic wave generator **10**, when it is assumed that the plane shape of the first electrode **1** and the second electrode **2** is a square of 5 mm×5 mm, the minimum separation distance is 5 mm, and a 10 nH coil L is coupled to the second electrode **2** in series, and when a voltage of 1 V is generated from the high-frequency voltage generation circuit B as shown in FIG. 2, it is known from a simulation that the voltage applied to the antenna terminal (the voltage applied between the point on the L side of C and GND) is substantially 2 V. The resistance R indicates the radiation resistance of the antenna. Further, it is also known that higher voltages are applied to the antenna as the inductance of the coil increases. By thus inserting a coil in series between the antenna constituted by the first electrode **1** and the second electrode **2** and the coaxial cable, the voltage between the antenna electrodes can be increased. Thereby, the electric field between the first electrode **1** and the second electrode **2** becomes stronger. The stronger the electric field applied to the ink, the more efficiently the ink is heated.

Role of Coil (3): Adding an Electric Field Generated by a Coil to an Electric Field Generated Between Electrodes to Enhance the Electric Field

The coil 3 is typically configured as a winding of a long electric wire of metal such as copper, which has a parasitic resistance as well as an inductance component. For example, when the inductance component is substantially 30 nH, the parasitic resistance is normally substantially 3Ω . Due to the inductance and the internal resistance, a potential difference is generated at both ends of the coil, and an electric field is generated at a place where the potential difference exists. FIG. 3 shows the results of a simulation of the electric field density distribution when the coil 3 is disposed in contact with the first electrode, and FIG. 4 shows the results of simulation of the electric field density distribution when the coil 3 is separated from the first electrode by substantially 4 mm. The electric field density in FIGS. 3 and 4 represent a higher value as the color approaches black to white. When a coil is installed in the immediate vicinity of the first electrode 1 as shown in FIG. 3, all of the increased voltages shown in the above "role of coil (2)" are applied to the first electrode, and a strong electric field is generated near the first electrode 1. Furthermore, when the direction of the electric field of the coil 3 and the direction of the electric field generated between the first electrode 1 and the second electrode 2 match, the electric field generated in the coil 3 overlaps with the electric field generated between the first electrode and the second electrode, thereby the electric field near the first electrode 1 is made stronger. In contrast to this, when the coil 3 in FIG. 4 is separated from the first electrode, the increased voltage shown in the above "role of coil (2)" is applied to the conductor 32 and the first electrode 1, and the electric field cannot be concentrated near the first electrode 1 where a strong electric field is required. At the same time, a strong unnecessary electric field is generated around the coil 3 distant from the first electrode 1 which does not require a strong electric field. In the structure shown in FIG. 3 and the structure shown in FIG. 4, in this example, the heating efficiency of the thin ink film T is 70% in the former case and substantially 8% in the latter case, thereby big difference occurs, and it is more effective to dispose the coil 3 as close as possible to the first electrode 1. For this purpose, it is possible to make the shape of the first electrode, for example, a meander shape to have an inductance, and to make the first electrode itself a coil, and omit the coil 3.

1.1.4. Variation of Disposition and Structure of Electrode

The electromagnetic wave generator may have a structure in which one of the first electrode 1 and the second electrode 2 is disposed so as to surround the other, as the electromagnetic wave generator 12 shown in FIG. 5. FIG. 5 is a schematic diagram showing the vicinity of the electrodes of the electromagnetic wave generator 12. In the electromagnetic wave generator 12, the first electrode 1 surrounds the second electrode 2.

The first electrode 1 of the electromagnetic wave generator 12 has a square shape in plan view. In the electromagnetic wave generator 12, the second electrode 2 has a hollow square shape in plan view. Although not shown, the shape of the first electrode 1 may be circular in plan view, and the shape of the second electrode 2 may be a ring or a hollow hexagon in plan view. The plane or spatial positional relationship between the first electrode 1 and the second electrode 2 and the structure of the coil 3 are the same as those of the above-described electromagnetic wave generator 10, and thus the description will be simplified.

In the electromagnetic wave generator 12, a high-frequency potential and a reference potential are fed to the rectangular first electrode 1 disposed at the center in plan view and the two electrodes 2 surrounding the first electrode 1, respectively. The coil 3 is inserted between the first electrode 1 and the inner conductor 4a of the coaxial cable 4, and it is important that the coil 3 is positioned as close to the first electrode 1 as possible.

In the electromagnetic wave generator 12, when the shape 10 of the second electrode 2 is a hollow rectangle in plan view, the length of one side of the outer periphery is, for example, 0.1 cm or more and 10.0 cm or less, desirably 0.3 cm or more and 5.0 cm or less, and more desirably 0.4 cm or more and 1.0 cm or less. Further, in this case, the width of the second 15 electrode 2 in plan view is 1.0 mm or more and 2.0 mm or less, desirably 1.4 mm or more and 1.6 mm or less, and more desirably substantially 1.5 mm.

In the electromagnetic wave generator 12, the minimum 20 separation distance d between the first electrode 1 and the second electrode 2 is $1/10$ or less of the wavelength of the electromagnetic wave output from the electromagnetic wave generator 12.

In the electromagnetic wave generator, as in the electromagnetic wave generator 14 shown in FIG. 6, one electrode 25 may continuously surround the other electrode and may be coupled to the outer conductor of the other coaxial cable via a continuous conductor, or the other electrode may be coupled to the inner conductor of the coaxial cable. FIG. 6 is a schematic diagram showing the vicinity of the electrodes 30 of the electromagnetic wave generator 14. In the electromagnetic wave generator 14, the inner conductor 4a of the coaxial cable 4 is coupled to the first electrode 1 via the columnar conductor 32, and the outer conductor 4b of the coaxial cable 4 is coupled to the second electrode 2 via the conductor 30. The conductor 30 continuously surrounds the periphery of the conductor 32.

The plane shape and disposition of the first electrode 1 and the second electrode 2 of the electromagnetic wave generator 14 are the same as those of the electromagnetic wave generator 12.

In the electromagnetic wave generator 14, the minimum 45 separation distance d between the first electrode 1 and the second electrode 2 is $1/10$ or less of the wavelength of the electromagnetic wave output from the electromagnetic wave generator 14.

Although not shown, in the electromagnetic wave generator 14, the conductor 30 may be integral with the second electrode 2. In this case, the conductor 30 becomes the second electrode 2. Similarly, the first electrode 1 of the electromagnetic wave generator 14 may be integrated with the columnar conductor 32. In this case, the conductor 32 becomes the first electrode 1.

In the electromagnetic wave generator 14, the second electrode 2 is a reference potential electrode, and the first electrode 1 is a high-frequency electrode. With the structure in which the high-frequency electrode is coupled to the inner conductor 4a of the coaxial cable 4 and the reference potential electrode is coupled to the outer conductor 4b of the coaxial cable 4 via a conductor, the electromagnetic wave generator 14 has a structure similar to a coaxial cable. Therefore, for example, the manufacturing becomes easier. Further, it has been found that the heating efficiency of the thin ink film is improved when the structure is the same as the electromagnetic wave generator 14.

In the electromagnetic wave generator 14, the second electrode 2 is a reference potential electrode, and the first electrode 1 is a high-frequency electrode. Furthermore,

when the conductor 30 coupled to the reference potential electrode continuously surrounds the conductor 32 coupled to the high-frequency electrode, the shield effect by the reference potential electrode is obtained, and the electromagnetic wave is less likely to leak outside the reference potential electrode. Further, a transmission mode is formed near the electrode, so that the thin ink film can be sufficiently irradiated with electromagnetic waves even when the distance between the thin ink film and the electrode is large.

In the electromagnetic wave generator 14, the width w of the second electrode 2 in plan view is 1.0 mm or more and 2.0 mm or less, desirably 1.4 mm or more and 1.6 mm or less. With such a structure, the heating efficiency of the thin ink film can be increased. Furthermore, the shape of the first electrode 1 in a plan view is desirably a rectangular shape (not shown) as compared with a square shape, for example, a rectangular shape of 0.5 mm×5.0 mm. With such a structure, the heating efficiency can be increased.

In each of the electromagnetic wave generators 12 and 14, the minimum separation distance d between the first electrode 1 and the second electrode 2 is $\frac{1}{10}$ or less of the wavelength of the output electromagnetic wave, and since the coil 3 is coupled to the second electrode 2 in series, an electromagnetic field can be efficiently generated near the device.

1.1.5. High-Frequency Source

The electromagnetic wave generator according to the present embodiment includes a high-frequency source. The high-frequency source includes the high-frequency voltage generation circuit B described above. The high-frequency source generates a high-frequency voltage applied to the first electrode 1 and the second electrode 2. The high-frequency source includes, for example, a quartz crystal oscillator, a Phase Locked Loop circuit, and a power amplifier. The high-frequency power generated by the high-frequency source is supplied to the first electrode 1 and the second electrode 2 via, for example, a coaxial cable.

The basic peripheral circuit configuration of the electromagnetic wave generator of the present embodiment is such that a high-frequency signal generated by a Phase Locked Loop circuit is amplified by a power amplifier and fed to the first electrode 1 and the second electrode 2. When a large number of sets of the first electrode 1 and the second electrode 2 are used, for example, one power amplifier may be used for one set of the first electrode 1 and the second electrode 2, and electromagnetic waves may be individually generated by dividing the output of the Phase Locked Loop circuit and transmitting the output to the power amplifier. Further, a plurality of power amplifiers may be used, and in such a case, the amplification factor of each power amplifier can be individually controlled more easily.

2. INK DRYER

The electromagnetic wave generator of the above embodiment can be used as an ink dryer. The ink dryer is the above-described electromagnetic wave generator, in which the first electrode and the second electrode 2 are disposed in parallel with respect to the thin ink film, and by applying a high-frequency voltage, the thin ink film can be heated very efficiently.

FIG. 7 is a schematic diagram of a disposition of the first electrode 1 and the second electrode 2 with respect to the thin ink film T as viewed from the side in the ink dryer 10 of the present embodiment. Since the ink dryer 10 is the same as the above-described electromagnetic wave genera-

tor 10, the same reference numerals as in the above description are assigned and the duplicated description is omitted.

2.1. Thin Ink Film

The thin ink film dried by the ink dryer 10 is a thin film obtained by attaching ink to a sheet such as paper or a film, a thin film obtained by attaching ink to a surface of a molded body having a three-dimensional shape or the like. The method for attaching the ink is not particularly limited, but may be an ink jet method, a spray method, a coating method using a brush, or the like. In the illustrated example, a thin ink film T formed by attaching ink on one side of a recording medium M using the ink jet method is illustrated.

The thickness of the thin ink film T is, for example, 0.01 μm or more and 100.0 μm or less, desirably 1.0 μm or more and 10.0 μm or less. Various components may be contained in the ink, and examples of components to be dried by the ink dryer 10 include water and an organic solvent. When water is contained in the ink, the frequency of the electromagnetic wave radiated from the ink dryer 10 is desirably from 1 MHz to about 30 GHz. In particular, the frequency is desirably set to 2.45 GHz used in a microwave oven, because the legal standard is clear.

The principle that the water in the ink is heated by the electromagnetic waves with which the ink film is irradiated is frictional heat generated by vibration of the water molecules due to the dielectric heating, and/or Joule heat generated by eddy current generated in the water. When the ink is an ink having a high ion concentration, such as dye ink, conductivity is generated, so that the effect of heating by Joule heat increases. In the ink dryer 10 of the present embodiment, since a vibration electric field is applied in parallel to the thin ink film T, both heating principles can be used.

2.2. Heating Mechanism

When electromagnetic waves (3 GHz) are incident on the surface of the water, although it depends on the temperature, the depth reached by the electromagnetic wave is substantially 1.2 cm at 20° C. This depth is called the skin depth. As described above, the thickness of the thin ink film is extremely thin as compared with the penetration depth of the electromagnetic wave. Therefore, when the thin ink film is irradiated with the electromagnetic wave perpendicularly, almost all electromagnetic waves penetrate, and water in the thin ink film can hardly be heated, or even when it can be heated, the efficiency becomes very poor.

According to a preliminary experiment conducted by the inventor, it has been found that even when a heating operation is performed with a sheet having the ink attached thereto in a microwave oven (microwave oven), the ink can hardly be heated. It is considered that the reason is that, the power, among the power of the electromagnetic waves with which the thin ink film is irradiated, that turns into heat inside the ink is very low by the electromagnetic wave penetrating the ink thin film.

As described above, the electromagnetic wave generator of the present embodiment generates a near electromagnetic field. That is, by disposing the thin ink film to the ink dryer at an appropriate distance, it is possible to irradiate in a narrow range around the thin ink film with the electromagnetic waves with concentration. Since the electromagnetic wave generated from the ink dryer of the present embodiment presents only in a nearby narrow space and has a very weak distant electromagnetic field, energy is less dissipated, and by appropriately disposing the thin ink film in the area where electromagnetic waves are present, the thin ink film can be heated very efficiently.

The mechanism of heating the thin ink film T by the ink dryer 10 will be described below. FIGS. 8 and 9 are schematic diagrams showing a mode in which the thin ink film T is disposed between the parallel plate electrodes E. FIG. 10 is an example of an equivalent circuit when the thin ink film T is disposed between the parallel plate electrodes E.

As shown in FIG. 8, when the thin ink film T is provided between the parallel plate electrodes E in parallel with the electrodes, even when a high-frequency voltage is applied to the parallel plate electrode E, the energy absorbed by the thin ink film T is very small. However, as shown in FIG. 9, when the thin ink film T is provided between the parallel plate electrodes E and perpendicular to the electrodes, the thin ink film T is heated very efficiently. Even with a thin ink film having the same volume and the same thickness, the heating efficiency can be increased 100 times by changing the direction of the thin ink film surface from horizontal to perpendicular with respect to the electrode.

FIG. 10 shows an equivalent circuit in the disposition shown in FIG. 9. As shown in FIG. 10, when the thin ink film T is provided between the parallel plate electrodes E and perpendicular to the electrodes, it is considered that this is equivalent to a circuit in which a capacitor CW where a space between the electrodes is filled with water and a capacitor CA where a space between the electrodes is filled with air are coupled in parallel. When a high-frequency voltage is applied in this circuit, the current and the electric field concentrate on the capacitor CW because the capacity of the capacitor CW is larger than the capacity of the capacitor CA. When the thin ink film T is made parallel to the direction of the electric field, the effect of increasing the distance that the electromagnetic wave passes through the thin ink film T and the effect of concentrating the electric field can be obtained, and the thin ink film can be heated very efficiently.

By forming the electric field in parallel with the thin ink film T, the heating efficiency of the thin ink film T is improved. Therefore, it is desirable that the direction of the electric field is as parallel as possible to the thin ink film T, and in the ink dryer 10 of the present embodiment, the first electrode 1 and the second electrode 2 having a structure capable of applying such an electric field are adopted. Further, as the electric field of the electromagnetic wave with which the thin ink film T is irradiated increases, the amount of heat generated by the thin ink film T increases. Since the electric field increases as the potential difference between the electrodes increases, the potential difference can be increased by disposing the coil 3 as described above. The coil 3 has an effect of impedance matching in addition to the effect of increasing the potential difference. Further, since the coil 3 itself generates an electric field, the coil 3 is disposed near the first electrode 1 or the second electrode 2, and the electric field generated by the coil 3 is added to the electric field generated between the electrodes to enhance the electric field and improve the heating efficiency.

2.3. Disposition of Electrode

The first electrode 1 and the second electrode 2 may be disposed perpendicular to the thin ink film T. For example, in the above-described electromagnetic wave generator 14, when the conductor 32 and the first electrode 1 are integrally formed and the conductor 30 and the second electrode 2 are integrally formed, the first electrode 1 becomes a columnar electrode, the second electrode 2 becomes a cylindrical electrode, and the extending direction becomes a direction of a normal line of the thin ink film T. In this case, when the electromagnetic wave generator 14 is installed so as to face

the thin ink film T, the first electrode 1 and the second electrode 2 are disposed with respect to the thin ink film T in a posture in which the extending direction extends in a direction perpendicular to the surface where the thin ink film T spreads. Even with such a disposition, the thin ink film T can be efficiently heated.

2.4. Conductor Plate

The ink dryer of the present embodiment may include a conductor plate. FIG. 11 is a schematic diagram of the vicinity of the electrodes of the ink dryer 16 provided with the conductor plate 5 and the disposition of the conductor plate as viewed from the side. The conductor plate 5 is disposed in parallel with the opposite side of the first electrode 1 and the second electrode 2 with respect to the thin ink film T. The conductor plate 5 is disposed at a position overlapping the first electrode 1 and the second electrode 2 in plan view. The thickness and plane size of the conductor plate 5 are not particularly limited.

The conductor plate 5 has conductivity. The conductor plate 5 is disposed to face the first electrode 1 and the second electrode 2 with the thin ink film T interposed therebetween, and thus it is possible to suppress a change in impedance of the ink dryer 16 due to the thin ink film T. Since the thin ink film T is regarded as a part of the capacitor C, the impedance of the ink dryer 10 changes depending on the thickness, volume, conductivity, and the like of the thin ink film T. In the above-described ink dryer 10 having no conductor plate 5, energy can be transmitted to the thin ink film T very efficiently, but the change in impedance of the ink dryer 10 becomes large.

The ink dryer 16 can suppress such a change in impedance by disposing the conductor plate 5. Further, by disposing the conductor plate 5, the energy may be transmitted to the thin ink film T more efficiently.

Regarding the conductor plate 5, for example, when the ink dryer 16 is provided in an ink jet printer, the platen can be formed of a conductive material and set as the conductor plate 5.

2.5. Operation Effect

According to the ink dryer of the present embodiment, the heating efficiency, that is, the ratio of the power, among the high-frequency power input to the antenna, used for increasing the temperature of the ink can be increased to 80% or more. According to the ink dryer of the present embodiment, the generated electromagnetic waves can be present only in a very limited area around the thin ink film. Thereby, the heating efficiency of the thin ink film is very good.

Since the ink dryer of the present embodiment uses a small electromagnetic wave generator having a minimum separation distance of $1/10$ or less of the wavelength of the electromagnetic wave, the ink dryer can be used with saving the power and a simple shield can be used even when it becomes necessary to suppress the scattering of electromagnetic waves. Further, since the power is saved, a high-frequency voltage generation circuit can be downsized.

Since the ink dryer of the present embodiment utilizes the near electromagnetic field, it is possible to suppress the propagation of the energy to an object such as a sheet on which the thin ink film is attached. Therefore, for example, even when the sheet is made of a material that is affected by the temperature, the sheet is not easily heated, so that the deterioration of the sheet can be suppressed.

3. INK JET PRINTER

The ink jet printer of the present embodiment includes the above-described ink dryer, a carriage that reciprocates a

recording medium in the width direction, and an ink jet head that discharges ink, and the ink dryer and the ink jet head are mounted on the carriage. FIG. 12 is a schematic diagram of a main part of the ink jet printer 200 of the present embodiment. FIG. 12 shows a carriage 50 and a recording medium M. The ink jet printer 200 includes an ink dryer 10 and the carriage 50.

The ink jet printer 200 includes an ink jet head 60 on the carriage 50 and a plurality of ink dryers 10. A first electrode 1, a second electrode 2, and a coaxial cable 4 of the ink dryer 10 are mounted on the carriage 50. Although not shown, the ink jet printer 200 includes a high-frequency source for driving each of the ink dryers 10. Further, although not shown, the plurality of ink dryers 10 are arranged so as to cover an area equal to or longer than the length of a nozzle row of the ink jet head 60 in a scanning direction SS of the recording medium M. The ink jet printer 200 is a serial type printer, and has a mechanism for moving the recording medium M and a mechanism for performing a reciprocation operation on the carriage 50.

The ink jet printer 200 forms a predetermined image on the recording medium M by repeating moving and disposing the recording medium M at a predetermined position, and discharging ink from the ink jet head 60 while scanning the carriage 50 in a direction intersecting the scanning direction SS of the recording medium M and attaching the ink to a predetermined position on the recording medium M with a predetermined amount, a plurality of times.

The ink dryer 10 is arranged in the carriage 50 on one side or both sides of the ink jet head 60 in the scanning direction MS of the carriage 50. In the illustrated example, a plurality of ink dryers 10 are arranged on both sides of the ink jet head 60 in the scanning direction MS. With this arrangement, the ink discharged from the ink jet head 60 and attached to the recording medium M to form a thin ink film can be dried quickly in a short time after a lapse of time in accordance with a moving speed of the carriage 50 and a distance from the nozzle of the inkjet head 60 to the ink dryer 10 in the scanning direction MS.

In FIG. 12, the ink dryers 10 are arranged in four rows on both sides of the ink jet head 60 in the scanning direction MS of the carriage 50. This is because, under the condition that 9 W of high-frequency power is input to the ink dryer 10 for drying the thin ink film, $\frac{1}{20}$ second is required, whereas the time required for the 5 mm ink dryer 10 to pass a specific coordinate at 1 m/s is $\frac{1}{200}$ second, which is short of $\frac{1}{20}$ second. The ink heating range of the 5 mm ink dryer 10 is set to 12.5 mm $\times$ 12.5 mm, and by arranging four of the ink dryers 10, the range of 50 mm $\times$ 50 mm can be heated simultaneously. Since it takes $\frac{1}{20}$ second for the 50 mm ink dryer 10 to pass the specific coordinates, the time required for drying can be secured.

In FIG. 12, the ink dryers 10 are arranged in five rows in a direction perpendicular to the scanning direction MS of the carriage 50. This is because the nozzle row of the ink jet head 60 has a length, and one ink dryer 10 of 5 mm $\times$ 5 mm cannot cover the length. The length of the nozzle row is set to 70 mm, and the length is covered by arranging five ink dryers.

The ink jet printer 200 of the present embodiment is particularly effective when the recording medium M is made of a material such as a film to which the ink does not soak or hardly soaks. However, even with a recording medium M that absorbs ink such as paper, a sufficient drying effect can be obtained.

3.1. Deformation of Disposition of Electromagnetic Wave Generator

FIG. 13 is a schematic plan view showing a carriage 50 of an ink jet printer 210 according to a modification example. In the ink jet printer 210, the electromagnetic wave generators 12 are arranged side by side in the direction in which the carriage 50 moves (the direction MS orthogonal to the scanning direction SS of the recording medium M), and in the scanning direction SS of the recording medium M, the electromagnetic wave generators 12 are arranged side by side.

In the ink jet printer 210, the electromagnetic wave generator 12 has a plane outer shape of a square, and a rectangular first electrode 1 and second electrode 2 are drawn. The minimum separation distance between the first electrode 1 and the second electrode 2 is as described above. The directions of the first electrode 1 and the second electrode 2 with respect to the direction MS in which the carriage 50 moves may be arranged in any manner. However, in order to irradiate a wide range of the electric field of the ink, it is better to increase an interval between the first electrode 1 and the second electrode 2. Although there is a gap between the electromagnetic wave generators 12, a gap may be provided to such an extent that the electromagnetic wave generators 12 are arranged such that there is no gap between the nearby electromagnetic fields generated from the electromagnetic wave generators 12.

The outer shape of the electromagnetic wave generator 12 is, for example, substantially 5 mm $\times$ 5 mm $\times$ height 8 mm, which is smaller than the plane size of the recording medium M. The drying speed of the thin ink film increases as the high-frequency power applied to the electromagnetic wave generator 12 increases. However, since the electromagnetic wave generator 12 itself generates heat due to the loss component of the electromagnetic wave generator 12, there are cases where there is a limit in increasing the high-frequency power to one electromagnetic wave generator 12. Therefore, it may be necessary to irradiate the thin ink film with electromagnetic waves over a certain time or more. Therefore, in the illustrated shape of the electromagnetic wave generator 12, the passing through time of one electromagnetic wave generator 12 with respect to the carriage 50 in the scanning direction MS may be insufficient, and a plurality of electromagnetic wave generators 12 are arranged in a total direction in the scanning direction MS of the carriage 50 so as to increase the heating time of the thin ink film. Further, in the shape of the illustrated electromagnetic wave generator 12, five are arranged in the SS direction. This is to cover the entire area of the ink jet head 60 in the SS direction.

FIG. 14 is a functional block diagram of the ink jet printer 200. A control section 70 is a control unit for controlling the ink jet printer 200. The interface section 101 (I/F) transmits and receives data between a computer 130 (COMP) and an ink jet printer 200. A CPU 102 is an arithmetic processor for controlling the entire ink jet printer 200. A memory 103 (MEM) is for securing an area for storing a program of the CPU 102, a work area, information on a thin ink film, and the like. The CPU 102 controls each unit by a unit control circuit 104 (UCTRL).

A transport unit 111 (CONVU) controls a sub-scanning of ink jet recording, and specifically controls a transporting direction and a transporting speed of the recording medium M. Specifically, the transporting direction and the transporting speed of the recording medium M are controlled by controlling a rotation direction and a rotational speed of a transport roller driven by a motor.

A carriage unit 112 (CARU) controls a main scanning (pass) of an inkjet recording, and specifically, reciprocates the inkjet head 60 in the scanning direction MS. The carriage unit 112 includes a carriage 50 on which the ink jet head 60 and the electromagnetic wave generator 10 are mounted, and a carriage moving mechanism for reciprocating the carriage 50.

A head unit 113 (HU) controls a type and a discharge amount of ink from the nozzles of the ink jet head 60. For example, when the nozzle of the ink jet head 60 is driven by a piezoelectric element, the operation of the piezoelectric element in each nozzle is controlled. The head unit 113 controls the timing of each ink attachment, the type of ink, the dot size, and the like. Further, the amount of ink attaching per scan is controlled by a combination of control of the carriage unit 112 and the head unit 113.

The electromagnetic wave unit 114 (EMU) controls constants of the high-frequency source or the configuration of the electromagnetic wave generator 10 based on the information on the thin ink film to be dried. For example, when the ink has a property that is difficult to dry, control is performed so that the output of the high-frequency source of the corresponding electromagnetic wave generator 10 is increased. Further, the electromagnetic wave unit 114 (EMU) can adjust the output of each of the plurality of existing electromagnetic wave generators 10 in accordance with an instruction from the control section 70. Note that when the output of the high-frequency source is adjusted, ON/OFF of the output may be adjusted in addition to the adjustment of the increase/decrease of the output. There is no need to heat an area on the recording medium M where no thin ink film exists. Therefore, it is desirable to turn off the high-frequency output in an area where there is no thin ink film. Further, as it is hard to cause color mixing, in an area where the interval between the thin ink films is large and the adjacent thin ink films are not in contact with each other, the high-frequency output may be turned off.

The ink jet printer 200 alternately repeats an operation of moving the carriage 50 on which the ink jet head 60 is mounted in the scanning direction MS and an operation of transporting the recording medium (sub-scanning). At this time, when performing each pass, the control section 70 controls the carriage unit 112 and the electromagnetic wave unit 114 to move the ink jet head 60 in the scanning direction MS, controls the head unit 113 to discharge ink droplets from predetermined nozzle holes of the ink jet head 60, and attaches the ink droplets to the recording medium, and controls the electromagnetic wave unit 114 to control the output of the electromagnetic wave generator 10 corresponding to a predetermined nozzle. Further, the control section 70 controls the transport unit to transport the recording medium M in the transporting direction by a predetermined transporting amount during the transporting operation.

In the ink jet printer 200, the main scanning (pass) and the sub-scanning (transporting operation) are repeated, so that the recording area on which a plurality of droplets are attached is gradually transported.

3.1. Control Section

The control section 70 controls the output of the electromagnetic wave generator 10 according to the information on the thin ink film formed by being discharged from the ink jet head 60 and attaching to the recording medium M. The information on the thin ink film is selected from a printing pattern, an amount of ink, an ink type, and composite information thereof.

In the ink jet printer 200 of the present embodiment, the control section 70 controls any one of the power of the high-frequency source, the frequency of the high-frequency source, the constant of the coil 3 (L), and the constant of the capacitor based on the information on the thin ink film.

Regarding the control of the power of the high-frequency source by the control section 70, as shown in FIG. 2, the power of the high-frequency source of the high-frequency voltage generation circuit B can be controlled and performed according to a signal from the electromagnetic wave unit 114 based on the signal of the control section 70. In this case, the power of the high-frequency source is controlled in a manner such as ON/OFF or adjusting the intensity.

Since the electromagnetic wave generator 10 has a high energy transmission efficiency with respect to the thin ink film, the thin ink film can be a part of a resonance system of the electromagnetic wave generator 10. Therefore, the impedance of the electromagnetic wave generation circuit A fluctuates depending on the printing pattern, the amount of ink, and the type of ink. When the impedance on the output side fluctuates and the matching with the impedance on the power feeding side deviates, it becomes difficult to feed power, and the heating efficiency of the thin ink film decreases. Therefore, the matching between the impedance on the output side and the impedance on the power feeding side is performed by controlling the frequency of the high-frequency source or controlling the coil and the capacitor, thereby improving the heating efficiency of the thin ink film.

Regarding the control of the frequency of the high-frequency source by the control section 70, as shown in FIG. 2, the frequency of the high-frequency source of the high-frequency voltage generation circuit B can be controlled and performed according to a signal from the electromagnetic wave unit 114 based on the signal of the control section 70. Although the control of the frequency of the high-frequency source does not directly match the impedance on the output side and the impedance on the power feeding side, when the impedance matching deviates, the resonance frequency deviates, and thus the heating efficiency of the thin ink film is improved by changing the frequency accordingly.

Regarding the control of the constant of the coil 3 (L) by the control section 70, for example, the coil 3 (L) may be used for impedance matching, and switching by the switch S may be performed according to a signal from the electromagnetic wave unit 114 based on a signal from the control section 70.

FIG. 15 is an equivalent circuit diagram of an electromagnetic wave generator 18 according to a modification example. In FIG. 15, the electromagnetic wave generation circuit A is represented by a symbol of an antenna.

The electromagnetic wave generator 18 is configured so that a plurality of coils L (3) can be switched by the switch S. An example of the switch S is a MEMS switch. The inductance of each of the plurality of coils L (3) is different, and switching to the coil L (3) having a specific inductance is performed according to a signal from the electromagnetic wave unit 114 based on a signal from the control section 70.

Regarding the control of the constants of the capacitors coupled to the first electrode 1 and the second electrode 2 by the control section 70, for example, a variable capacity capacitor CV is coupled to the first electrode 1 and the second electrode 2, and the capacity of the variable capacity capacitor can be adjusted according to a signal from the electromagnetic wave unit 114 based on a signal from the control section 70.

FIG. 16 is an equivalent circuit diagram of an electromagnetic wave generator 19 according to a modification example. In FIG. 16, the electromagnetic wave generation circuit A is represented by a symbol of an antenna. In the electromagnetic wave generator 18, a variable capacity capacitor CV is coupled to wiring branched from between the high-frequency voltage generation circuit B and the coil L (3) to a reference potential. The capacitance of the variable capacity capacitor CV can be changed according to a signal from the electromagnetic wave unit 114 based on a signal from the control section 70.

The control section 70 may send the calculated result of the optimum value of the output of the electromagnetic wave generator 10 according to the information on the thin ink film by the CPU or the like to the electromagnetic wave unit 114, as an output signal. Further, the optimum value of the output of the electromagnetic wave generator 10 according to the information on the thin ink film may be stored in advance in the memory 103 using a table or the like, and a value which the control section 70 reads from the memory 103 based on the information on the thin ink film may be sent to the electromagnetic wave unit 114 as an output signal. By doing so, the time for a calculation can be reduced, and the recording speed of the ink jet printer 200 can be improved. Note that although an example in which the electromagnetic wave unit 114 is controlled using the control section 70 and the memory 103 included in the ink jet printer 200 has been described, a similar control may be performed by providing a dedicated control section, a memory, and the like for the electromagnetic wave generator 10.

FIG. 17 is an equivalent circuit diagram of an electromagnetic wave generator 20 according to a modification example. In FIG. 17, an impedance matching circuit D is provided between the electromagnetic wave generation circuit A and the high-frequency voltage generation circuit B. The impedance matching circuit is normally a circuit constituted by a n-type coil 100 and a capacitor. The tip of the two wirings extending below the shape of n is normally coupled to GND (reference potential). The impedance matching circuit D performs the "role of coil (1)" described above, and improves the voltage transmission efficiency. Note that in this specification, the coil L (3) in FIG. 17 may be referred to as a first coil, and the coil L (100) may be referred to as a second coil.

The above is an example of a serial type ink jet printer in which an ink jet head and an electromagnetic wave generator are mounted on a carriage. However, the ink jet printer of the present embodiment may be of a line type, or may be of a type in which an electromagnetic wave generator is not mounted on a carriage but is mounted on a main body.

4. EXPERIMENTAL EXAMPLE

Hereinafter, the present disclosure will be further described with reference to experimental examples, but the present disclosure is not limited to the following examples.

FIG. 18 shows an example in which the resonance frequency or impedance of the electromagnetic wave generator fluctuates with the printing pattern of the thin ink film obtained by simulation. The upper part in FIG. 18 shows a simulation result of the electromagnetic wave generator having a structure shown in the graph (corresponding to the above-described electromagnetic wave generator 14) and the thin ink film surrounded by a rectangle, and shows a graph of a characteristic curve of the resonance frequency. In

the example shown in the upper part in FIG. 18, the entire electromagnetic wave generator faces the thin ink film.

The middle part in FIG. 18 differs from the upper part in the shape of the thin ink film, shows a simulation result when substantially a quarter of the electromagnetic wave generator faces the thin ink film, and shows a graph of a characteristic curve of the resonance frequency. The lower part in FIG. 18 does not have a thin ink film, shows a simulation result when the electromagnetic wave generator does not face the thin ink film, and shows a graph of a characteristic curve of the resonance frequency.

FIG. 18 shows that when the printing pattern is changed, the frequency at which the return loss of energy is minimized changes. In this case, not only the frequency changes, but also the intensity and shape of the peak change. From these results, it can be said that by performing impedance matching and changing the frequency according to the information on the thin ink film, the thin ink film can be more efficiently heated.

The present disclosure is not limited to the embodiments described above, and various modifications are possible. For example, the present disclosure includes substantially the same configurations, for example, configurations having the same functions, methods, and results, or configurations having the same objects and effects, as the configurations described in the embodiments. Further, the present disclosure includes a configuration obtained by replacing non-essential portions in the configurations described in the embodiments. Further, the present disclosure includes a configuration that exhibits the same operational effects as those of the configurations described in the embodiments or a configuration capable of achieving the same objects. The present disclosure includes a configuration obtained by adding the configurations described in the embodiments to known techniques.

What is claimed is:

1. An ink jet printer comprising:
an electromagnetic wave generator including
an electromagnetic wave generation section that generates an electromagnetic wave,
a high-frequency voltage generation section that generates a voltage applied to the electromagnetic wave generation section, and
a transmission line that electrically couples the electromagnetic wave generation section and the high-frequency voltage generation section to each other in which
the electromagnetic wave generation section includes a first electrode, a second electrode, a first conductor that electrically couples the first electrode and the transmission line to each other, and a second conductor that electrically couples the second electrode and the transmission line to each other,
one of the first electrode or the second electrode is a reference potential electrode to which a reference potential is applied and the other is a high-frequency electrode to which a high-frequency voltage is applied,
a minimum separation distance between the first electrode and the second electrode is $1/10$ or less of a wavelength of an output electromagnetic wave,
a minimum separation distance between the first conductor and the second conductor is $1/10$ or less of a wavelength of an output electromagnetic wave, and
the first conductor further includes a coil, and the coil is disposed at a position closer to the first electrode than the transmission line; and

21

an ink jet head discharging ink, wherein
a plurality of the electromagnetic wave generators are
provided and the electromagnetic wave generators are
moved relative to a recording medium,
a thin ink film of the ink discharged from the ink jet head
and attached to the recording medium is heated and
dried by the electromagnetic wave generator, and
a control section that controls a power or a frequency of
the high-frequency source according to information on
the thin ink film is further included.

2. The ink jet printer according to claim 1, further
comprising:

a memory storing an optimum value in accordance with
the information on the thin ink film, wherein
the control section controls the power or the frequency of
the high-frequency source with reference to the optimum
value.

3. The ink jet printer according to claim 1, wherein
the information on the thin ink film is selected from a
printing pattern, an amount of the ink, a type of the ink,
and a combination thereof.

4. An ink jet printer comprising:

an electromagnetic wave generator including
an electromagnetic wave generation section that gen-
erates an electromagnetic wave,
a high-frequency voltage generation section that gen-
erates a voltage applied to the electromagnetic wave
generation section, and
a transmission line that electrically couples the elec-
tromagnetic wave generation section and the high-
frequency voltage generation section to each other in
which
the electromagnetic wave generation section includes a
first electrode, a second electrode, a first conductor
that electrically couples the first electrode and the
transmission line to each other, and a second con-
ductor that electrically couples the second electrode
and the transmission line to each other,

35**22**

one of the first electrode or the second electrode is a
reference potential electrode to which a reference
potential is applied and the other is a high-frequency
electrode to which a high-frequency voltage is
applied,

a minimum separation distance between the first elec-
trode and the second electrode is $1/10$ or less of a
wavelength of an output electromagnetic wave,
a minimum separation distance between the first con-
ductor and the second conductor is $1/10$ or less of a
wavelength of an output electromagnetic wave,
a first coil is coupled to the first electrode or the second
electrode in series,

the first conductor includes the first coil, and the first
coil is disposed at a position closer to the first
electrode than the transmission line, and
an impedance matching circuit constituted by a second
coil and a capacitor is coupled between the first coil
and the high-frequency source; and

an ink jet head discharging ink, wherein
one or more electromagnetic wave generators are pro-
vided and the electromagnetic wave generator is moved
relative to a recording medium,
a thin ink film of the ink discharged from the ink jet head
and attached to the recording medium is heated and
dried by the electromagnetic wave generator, and
a control section that controls a constant of the second coil
or a constant of the capacitor of the impedance match-
ing circuit according to information on the thin ink film
is further included.

5. The ink jet printer according to claim 4, further
comprising:

a memory storing an optimum value in accordance with
the information on the thin ink film, wherein
the control section controls the constant of the second coil
or the constant of the capacitor of the impedance
matching circuit with reference to the optimum value.
